United States Patent Office

Des. 198,562
Patented July 7, 1964

198,562

TEXTURED ARTIFICIAL SPONGE OR SIMILAR ARTICLE

Alfred Politzer and Frank Pekarek, Cleveland, Ohio,
assignors to Nylonge Corporation, Cleveland, Ohio, a
corporation of Ohio

Filed Sept. 17, 1962, Ser. No. 71,733

Term of patent 14 years

(Cl. D9—2)

Des. 198,562

PAGE 2

T1 Q. 6.

T 1 Q.7.

T 1 Q.8.

FIGURE 1 is a plan view of a section of textured artificial sponge or similar article, showing our new design;

FIGURE 2 is a fragmentary section thereof along line 2-2 in FIGURE 1;

FIGURE 3 is a fragmentary section thereof along line 3-3 in FIGURE 1;

FIGURE 4 is a fragmentary section thereof along line 4-4 in FIGURE 1;

FIGURE 5 is a fragmentary section thereof along line 5-5 in FIGURE 1;

FIGURE 6 is an enlarged detail plan view of FIGURE 1;

FIGURE 7 is an end elevational view of the sponge of FIGURE 1; and

FIGURE 8 is a side elevational view thereof. The dominant features of our design reside in the features shown in full lines.

We claim:

The ornamental design for textured artificial sponge or similar article, as shown and described.
